UNITED STATES PATENT OFFICE

CHARLES E. JOHNSON, OF MUSKEGON, MICHIGAN, ASSIGNOR TO THE PISTON RING COMPANY, OF MUSKEGON HEIGHTS, MICHIGAN, A CORPORATION OF MICHIGAN

PRESSURE HEAD FOR PISTON-RING GRINDERS

Application filed May 31, 1927. Serial No. 195,207.

This invention relates to improvements in pressure heads for piston ring grinders and it is particularly an improvement of the pressure head shown in Patent No. 1,551,156, 5 issued August 25, 1925. The pressure head embodying this invention is intended to be used with the same type of piston ring grinding machine shown in said patent and for the same purpose as the pressure head shown 10 in said patent, namely, the pressing of a piston ring against a grinding wheel as the ring is moved across the face thereof.

In the manufacture of piston rings it is very desirable to submit them to a flattening 15 process for the purpose of making one face of the ring absolutely flat or true. This flattening process must be performed upon one surface of the ring while the ring is in its natural undistorted condition and is preferably performed by passing the ring over and against the surface of a grinding wheel and pressing or holding the ring against the grinding wheel with sufficient pressure to enable the grinding wheel to grind the 20 surface of the ring. The pressure must be uniformly applied to all parts of the ring and must not be sufficient to distort the ring during the process.

A difficulty experienced by use of the pressure head of the above mentioned patent 30 and other analogous devices has been that a uniform pressure was not obtained unless the ring was located exactly centrally of the pressure head and in the machine by which 35 this flattening process is performed it is not expedient to provide for the exact centralizing of the ring relative to the pressure head. Another difficulty arising in the use of prior devices has been a tendency to distort the ring by pressure upon it. Owing to the fact that recent mechanisms utilize a much narrower ring than was formerly customary, the rings now being made in some 40 cases as narrow as $\frac{1}{16}$ th of an inch, devices which would practically operate with the former wider and consequently more rigid rings are not satisfactory with the present narrower and more flexible rings. In addition to this engineering specifications call for 45

a much more perfect fit of the ring now than heretofore.

The pressure head embodying the present invention is intended to overcome all of the defects and inefficiencies of former devices 55 of this character and is adapted to engage a piston ring located beneath it whether centrally of it or not and to press all portions of it with equal pressure against the surface of a grinding wheel as the ring is moved over 60 it. The invention is provided with various novel features of construction and arrangement hereinafter more fully described and particularly pointed out in the claims, reference being had to the accompanying drawings, 65 in which:

Fig. 1 is a plan view of a grinding wheel and a portion of the machine used to pass the ring over the surface thereof showing several of the pressure heads embodying this 70 invention operatively applied thereto.

Fig. 2 is an enlarged fragmentary sectional elevation of the same on the line 2—2 of Fig. 1.

Fig. 3 is an enlarged, approximately full 75 size, vertical section of the pressure head operatively engaging a piston ring.

Fig. 4 is an inverted plan view of the pressure head with a piston ring located 80 against it, and

Fig. 5 is a fragmentary plan view of the pressure head.

Like reference characters refer to like parts in the different figures of the drawings.

The grinding machine with which the pressure head embodying this invention is used 85 comprises a horizontally disposed grinding wheel 1 and a rotating disk 2 which overlaps a part of the horizontal grinding surface of the grinding wheel. The disk has a plurality of circular openings 3 spaced about it near its periphery, each opening being large enough to loosely receive a piston ring. The disk near its periphery is thinner than the ring to be ground. A feeding device 4 is provided which deposits the rings one at a time, in the respective openings as the disk rotates and these rings are carried by rotation of the disk across and in engagement with the horizontal surface of the grinding wheel. 90 95 100

A plurality of pressure heads 5, one for each opening 3 is provided, each pressure head being located above its respective opening and each pressure head is carried on the 5 outer end of an arm 6, said arms being pivotally mounted in blocks 7 on the disk near its center. The inner end of each arm is provided with a cam roller 8 which traverses the under side of a stationary cam 9 by means of which the outer ends of the 10 arms and the pressure heads thereon may be raised or lowered for the purpose hereafter described.

The pressure head comprises a substantially 15 circular disk shaped body 10 which has a lug 11 centrally located on its upper side to which the outer end of the arm 6 is pivotally attached. A plurality of weights 12 are annularly arranged and located under the 20 body 10 these weights each being of the same weight and the weights are preferably elongated rectangular in shape having flat lower surfaces and extending radially from the axis of the head. Each weight is independently 25 mounted on the body 10 of the head by two vertical stems 13 which extend through corresponding openings 14 in the body and are provided with retaining means such as cotter pins 15 above the body. The stems are sufficiently long so that a limited vertical movement is allowed for each weight relative to 30 the body and the holes 14 are enough larger than the stems 13 so that an absolutely free movement without binding or cramping is 35 obtained. The lower surfaces of the weights which are annularly arranged include or cover an annular area considerably larger than the ring which is to be performed upon.

In use the pressure heads are located substantially centrally over the openings 3 in the disk 2 but a variety of sizes of rings are ground with the machine using the same diameter openings 3 and for this reason, especially when a ring considerably smaller than the opening 3 is used the ring will not be located exactly centrally under the pressure head. The rings 16 are deposited in the openings 3 by the feeding device 4 and as the disk rotates the respective pressure heads are lowered upon the rings at approximately the same time that the rings are carried upon the grinding wheel, this lowering of the pressure head being accomplished by movement of the arm 6, the inner end of 55 which is acted upon by the stationary cam 9. The cam 9 is so shaped that, when the head is lowered, the weights 12 will be brought into engagement with the upper surface of the ring 16 and the body 10 will be lowered sufficiently to release all of the 60 weights but will be held high enough so that it will not engage the weights, this position being illustrated in Fig. 3. The head is held in this position during the movement of the 65 ring across the grinding wheel. Just before

the ring leaves the grinding wheel it is desirable to raise the head completely from the ring which is done by action of the cam 9 against the inner end of arm 6 and as the body 10 rises the retainers 15 will engage 70 its upper surface and lift the weights from the ring. The heads are held in this raised position until they pass the feeding device and are again lowered in engagement with a ring to be passed over the grinding wheel. 75

By means of this device it will be seen that the ring is pressed against the grinding wheel by engagement with its upper surface of the plurality of weights only, the weight of the body 10 not being exerted upon the ring. Inasmuch as each of the weights 12 is independently movable it will bear against that portion only of the ring directly beneath it and therefore an uneven surface of the ring will have no effect upon the pressure at its various points. Each weight will exert its own independent pressure upon the ring at its respective point and as the weights are uniform the pressure at all points of the ring will be uniform. If the ring is not located exactly centrally of the pressure head it will not result in uneven pressure in a greater pressure on one side than on the other since the pressure is not applied centrally of the pressure head as in former structures but 95 each weight acts independently and exerts its own pressure.

Pressure heads of different proportions are provided for different sizes and widths of rings, a narrow easily flexed ring being used with a pressure head having relatively light weights while a wider stiffer ring will use a pressure head having heavier weights. Extreme changes in diameters of the rings will require a pressure head of different diameter but a pressure head of the same diameter will operate upon rings of various diameters within certain limits. 100

Although this invention has been described in its adaptation for grinding piston rings 110 it is conceived that the same principle may be utilized for other purposes and it is to be understood that the scope of the claims is not to be limited strictly to the use of the invention in piston ring grinding. 115

I claim:

1. A grinding machine for piston rings comprising a grinding wheel, a disk having a portion with openings to receive piston rings mounted to rotate with said portion over the grinding wheel, a pressure head located over each of said openings, each pressure head comprising a body and a plurality of weights connected to the body, each weight having a limited independent movement relative to the body and means for lowering the pressure head to engage the weights with the ring in the opening and to suspend the body with its weight free from said weights. 120

2. A grinding machine for piston rings 130

comprising a grinding wheel, a disk having a portion with openings therethrough adapted to be rotated across the face of said grinding wheel, each opening adapted to receive a piston ring, arms pivotally mounted on said disk each with an end thereof adjacent one of said openings, a pressure head located above each of said openings and attached respectively to the end of the arm adjacent said opening, 5 each pressure head comprising a body and a plurality of weights, each weight independently connected to the body for limited movement relative thereto and means actuating upon said arm for lowering the pressure head to engage the weights with a piston ring in said opening and to suspend said body with its weight free from said weights.

3. In a device of the class described, means for guiding an article to be worked upon, a 20 pressure head located above said guiding means and an article therein, said pressure head comprising a body and a plurality of weights connected to said body and adapted to engage said article at different points, 25 each weight being mounted for independent movement relative to the body and to each other and means for holding the body with the weights in engagement with said article and with its weight free from said weights.

30 4. In a device of the class described, a guide for an article to be worked upon, a pressure head located above said guide and an article therein, said pressure head comprising a body and a plurality of annularly arranged weights adapted to engage said body at different points, said weights being mounted on said body for independent vertical movement relative to the body and to each other and means for lowering the pressure head to engage the weights with the article and for holding the body with its weight free from the weights.

35 5. In a device of the class described, a guide for an article to be worked upon, a pressure head located above said guide and above an article therein comprising a body, a plurality of elongated weights annularly arranged beneath said body, each weight extending radially from the axis of the annulus, 50 two stems extending upwardly from each other and passing freely through the body and means at the upper ends of the stems for retaining the stems in the body and for permitting a limited movement of the stems in the body.

55 6. In a device of the class described, means for supporting an article to be worked upon, a pressure head associated with said supporting means and an article thereon, said pressure head comprising a body and a plurality of weights connected to said body and adapted to engage said article at different points, each weight being mounted for independent movement relative to the body and to each other and means for holding the body with

the weights in engagement with said article and with its weight free from said weights.

7. In a device of the class described, means for supporting an article to be worked upon, a pressure head associated with said supporting means and an article thereon, said pressure head comprising a body and a plurality of annularly arranged weights adapted to engage said body at different points, said weights being mounted on said body for independent vertical movement relative to the body and to each other and means for lowering the pressure head to engage the weights with the article and for holding the body with its weight free from the weights.

8. In a device of the class described, means for supporting an article to be worked upon, a pressure head associated with said supporting means and an article thereon, said pressure head comprising a body, a plurality of elongated weights annularly arranged beneath said body, each weight extending radially from the axis of the annulus, two stems extending upwardly from each other and passing freely through the body and means at the upper ends of the stems for retaining the stems in the body and for permitting a limited movement of the stems in the body.

In testimony whereof I affix my signature.

CHARLES E. JOHNSON.
